MOUNTING FOR A TWO-BASE ELECTRIC
TUBULAR LAMPKurt Wiegand, Berlin-Neu-Tempelhof, Germany,
assignor to General Electric Company, a corporation of New YorkApplication December 23, 1935, Serial No. 55,924
In Germany January 23, 1935

3 Claims. (CL 173—328)

Two-base electric tubular lamps, namely such which have a luminous wire stretched out in the direction of their axis, are often arranged in an uninterrupted train lying together axially, in order to form luminous lines, script-symbols, ornaments, figures etc. Such lamp installations in the first place necessitate the laying of current conductors from which branches lead to the mountings of the individual tubular lamps.

10 The object of the invention is to build the mountings of such tube lamps in such a manner that the time of laying of the conducting wires as well as the connecting of the mountings of each lamp of the installation is eliminated. For 15 this purpose, according to the invention the caps of both two-part single mountings for a tube lamp are united into a common structure by means of two conducting-rods or -wires which serve to conduct current to and along the installations.

20 The bare end parts of the conducting rods lie inside of the mounting caps. The mounting bases are equipped with attachment pins or attachment sleeves, so that additional lamps may be connected to the first one. Since current 25 conduction to and along the installation occurs in this manner by means of the conducting rods, the otherwise customary separately laid current conductors are unnecessary. In addition to this the relative position of the two single-mountings 30 of one lamp are fixed.

With this construction of the mounting it is preferable that on one side of each mounting-base a spring clip is arranged and on the other side of the same are two spring clips which are bridged only by the bare end part of the inserted conducting rods. Thus, only when the cap-structure is inserted, is the current circuit closed, so that actually all danger of touching current carrying contact parts is avoided during insertion or exchange of a tube lamp.

On the drawing is shown, by way of example, a construction of the new mounting.

Fig. 1 shows one end of the new mounting in a perspective view.

45 Fig. 2 is a cross section through the single mounting along line II—II of Fig. 3.

Fig. 3 is a longitudinal section through the single-mounting on the line III—III of Fig. 2.

50 Fig. 4 shows the wiring diagram of adjacently placed mountings.

The tubular lamps to be mounted show the usual construction. They have a cylindrical glass vessel 1 and a tungsten helical wire 2 which is stretched out in the axial direction of the latter, 55 which wire is carried by a support structure 3

and lies conductively against the metal discs 4 which are fused into the ends of the vessel 1, or are fastened to them. For each tubular lamp two single mountings are required, each of which consists of a mounting base 5 and a cap 6. Each 5 mounting base 5, in a deep side groove 7, contains two spring clips 8, 9, of which the first leads to an attachment pin 10 and the latter to a ring shaped contact plate 11. In the mounting base 5, a second side groove 12 is provided, in 10 which is arranged a spring clip 14, which is conductively connected with a second attachment pin 13.

Each cap of the single-mountings consists of a frontal wall 15, two side walls 16 and an arc-shaped cover-strip 17 of narrow width. The two caps 6 are united into a rigid structure by means of two conducting-rods or -wires. The conducting rods 18, 19, in their free length between the caps, are provided with an insulating coating, 20 their end parts 21, however, which lie in the recesses 20 of the caps 6, are not insulated. The frontal wall 15 of each cap 6 is further provided with two slots 22, 23.

In placing the new mounting, the two mounting bases 5 are united with the proper cap structure while the bare end parts 21 of the conducting rods 18, 19 are gripped by the spring clips 8, 9 or by the clip 14 of the mounting bases. The entire mounting arrangement is then placed 30 against the wall or against a wood strip 24 and both mounting bases 5 are finally fastened by screws. Thereupon the cap structure 6, 18, 19 is lifted off and the tubular lamp 1 is inserted between the contact plates 11, which can occur 35 without danger since the spring clips 9, which are connected with the contact plates 11, are not connected with the accompanying spring clips 8. Thereupon the cap structure is put in place again and the lamp installation is then ready for 40 operation. As many lamps as desired can now be placed together, as shown in Fig. 4, since two single mountings of two adjacent lamps, which are placed with their frontal surfaces together, are always connected with each other by means 45 of the attachment pins 10, 13 and the attachment sleeves 10', 13'. The connections to and along such an installation are shown in Fig. 4. The current which is conducted to the two spring clips 8 and 9 of each mounting reaches the attachment pin and the next lamp by means of the former and reaches the spring contact plate 11 by means of the second clip 9, so that the lamp receives current only after the cap structure has been put in place. At the same time the 50 55

clip 14 of the mountings is connected to the current which is carried to the neighboring lamps through the connected attachment pins 10, 13.

As has been already mentioned, each lamp is connected with a potential only when the cap structure is put in place, so that when the cap structure is taken off, work can be done, without further ado, on the mountings or on the lamps or the lamp itself can be exchanged. The contact protection of the new mounting is increased by the fact that the bare end parts of the conducting rods lie in recesses of the mounting caps which are accessible only from the bottom, and the spring clips 8, 9 and 14 lie in deeply cut grooves of the mounting bases 5.

In order to make the two conducting rods, which come to lie on both sides of each tubular lamp, invisible to the observer, a reflector can be placed between them and the tubular lamp, which also throws forwards the light which otherwise would be radiated backward.

The new mounting can also be used with equal success for soffit lamps and for tubular lamps constructed in other ways.

25 What I claim as new and desire to secure by Letters Patent of the United States is:

1. A mounting for a two-base electric tubular lamp comprising a base for each end of the lamp, contact pins secured to one of said bases, contact 30 clips electrically connected to said contact pins and secured to said one of said bases, contact sleeves secured to the other of said bases, contact clips electrically connected to said contact sleeves and secured to said other of said bases, a 35 contact plate secured to each of said bases for connecting the two ends of said lamp, a contact clip connected to each of said contact plates and secured to said bases, a cap of insulating material for covering each end of the lamp, and rods

secured to said caps forming a unitary structure and having bared ends for connecting said last named contact clips to one of said first named contact clips whereby electrical connection is completed to said contact plates.

2. A mounting for a two-base electric tubular lamp comprising a base for each end of the lamp, a contact clip secured to each side of each of said bases, a contact plate secured to each of said bases and electrically connected to one of said 10 contact clips on its corresponding base and adapted to engage the opposite ends of the lamp, caps of insulating material adapted to cover the ends of said lamp, and a rod disposed on each side of said bases securing said caps together to 15 form a unitary structure and having bared ends to engage the contact clips on a corresponding side of said bases completes the electrical connections to said lamp.

3. A mounting for a two-base electric tubular lamp comprising a base for each end of the lamp, two contact clips juxtaposed at one side of one base and a single contact clip located at the other side of said base, two juxtaposed contact clips located at one side of the other base in 25 line with the single contact clip of the first mentioned base, a single contact clip secured to the other base in line with the two juxtaposed contacts of the first mentioned base, a contact plate secured to each of said bases and electrically 30 connected to one of said juxtaposed contact clips on its corresponding bases and adapted to engage opposite ends of the lamp, caps of insulated material adapted to cover the ends of the lamps, and rods connected to said caps and having bared ends to interconnect the single and juxtaposed contact clips on corresponding sides of said bases.

KURT WIEGAND.
